CLAIM

The ornamental design for a printer, as shown and described.

DESCRIPTION

FIG. 1 is a top perspective view of a printer according to our new design;

FIG. 2 is a bottom perspective view thereof;

FIG. 3 is a top side elevation view thereof;

FIG. 4 is a bottom plan view thereof;

FIG. 5 is a right side elevation view thereof;

FIG. 6 is a left side elevation view thereof;

FIG. 7 is a front elevation view thereof; and,

FIG. 8 is a rear elevation view thereof.

The dot-dash broken lines and the broken lines that are immediately adjacent to the claim, and define unshaded regions, represent the bounds of the claim while all other broken lines are directed to environment. The broken lines form no part of the claimed design.
